2,175,775

METHOD OF WINDING CARTRIDGES

James E. Hurn, La Porte, Ind., assignor to De
Luxe Products Corporation, a corporation of
Indiana

Application August 30, 1937, Serial No. 161,717

7 Claims. (Cl. 210—131)

This invention is a method of and mechanism for clarifying and filtering lubricating oil, and more particularly for freeing lubricating oil in an internal combustion engine from impurities.

Oil filters heretofore produced for internal combustion engines have attempted to procure filtering primarily by the use of straining means which will in time build up a layer of impurities sufficient to procure better filtering. The present invention is directed toward the use of a thick body of absorbent filtering medium through which oil is seeped under low velocity. In this manner, it is possible to divert only a small portion of the oil employed in an internal combustion engine and filter it so thoroughly that visual cleanliness as well as the necessary chemical cleanliness is maintained in the whole body. Experience has shown that with a filtering of the type herein described, oil may be used without change during fifty thousand miles or more of driving.

The invention is illustrated in the drawings, in which—

Fig. 1 is a sectional elevation of a filter designed for use on an ordinary passenger automobile, the filter being drawn to scale; Fig. 2 is a sectional elevation of the helical spring supporting means within the cartridge of the filter; Fig. 3 is a detailed sectional view of the valve; Fig. 4 is a sectional elevation illustrating a dual filtering system; Fig. 5 is a sectional plan of an apparatus for forming a cartridge and having thereon a cartridge partially formed; Fig. 6 is an elevation of a metallic cartridge cover; and Fig. 7 is a view of a cartridge.

As illustrated in the drawings, 1 represents a filter housing, 2 is a cover enclosing the top thereof, and 4 represents a sump portion which is provided with a shoulder 3 adapted to support a cartridge. A tubular member 5 is fixedly seated in the bottom of the sump 4 and extends upwardly and centrally through the filter. The upper end of the tube is preferably threaded and a threaded extension 10 fitted therein. At the base of the filter an oil inlet 6 is provided which is tapped on to the pressure line leading from the internal combustion engine in such manner as to produce parallel flow through the filter. The diameter of the inlet 6 for an ordinary combustion engine is $\frac{1}{8}$ " internal diameter, taking off from a pressure line which is usually at least $\frac{3}{8}$ ". The inlet line is markedly narrowed at the passage 7, this passageway having an internal diameter of $\frac{1}{8}$ " on a truck size filter and $\frac{5}{16}$ " on a passenger car filter. The passageway 8 and the

tubular member 5 are $\frac{3}{8}$ " in diameter. In an upper portion of the tube, two openings 9 are provided $\frac{1}{8}$ " in diameter, through which oil is passed in a rapidly moving thin stream against the cone 11. This cone is made preferably of a rigid material, for example, thin sheet metal, say of 30 gauge, and preferably is integrally connected to the filtering cartridge. Its upper portion is unbroken and its lower portion is provided with a large number of small perforations 12 through which oil passes into the filtering medium 13. The base 14 of the cone is seated upon the shoulder 3 of the sump 4.

Within the cartridge are provided means for supporting the normal resistance of the filtering medium to compression, which properly is in the form of a helical spring 15 which is affixed to the base 14 by welding or preferably by insertion of an end 16 of the spring in a groove 17 in the base. The filtering medium preferably consists of cellulosic fibers, which have the property of reacting with any sulfuric acid formed in the engine and thereby removing the same. The fibers should be extremely long and interconnected to prevent any possibility of channeling and should be dense enough to prevent compression, but not too dense to prevent free seepage of oil therethrough. The preferred method of forming a cartridge will be set forth hereinafter.

A sack or bag 18 is attached to the top 19 of the cone 11 and surrounds the filtering medium, its other end 20 being fastened over the base of the cone, for example, by a shirr string.

The cartridge 20 so formed, fits about the tubular member 5 and within the housing 1. It is 35 surmounted at the top by the perforated cap 22, shown in detail in Fig. 6. The nut 23 is threaded on the extension 10, thus securing the cap 22 to it as a unit, and permitting removal of the cover at the same time as the extension 10 is removed. 40 The extension 10 is pierced by the narrow passageway 24. The size of this passageway is correlated to the oil filtering capacity of the cartridge and the size of the inlet 6 so that when the ball valve 25 is open the capacity of the filter will 45 be substantially the same as the amount of oil admitted at the bottom, and thus will not build up pressure or substantially reduce it. The size of the passageway will depend upon the characteristics of the cartridge and also upon the 50 characteristics of the oil employed. For most purposes, a diameter of $\frac{5}{32}$ " is desired. This extension is shown in detail in Fig. 3. The ball valve 25 closes on the seat 26, which should be smooth and cut back sharply enough to provide

full flow for opening of the valve. The valve is held normally in closed position by the spring 27 which may be adjusted by the screw 28. A plug 29 is provided above the seat screw fitting 5 against the shoulder 30 in the wheel 31. The upper portion of the extension 10 forms an enlarged knob 32 which is transversely pierced by the handle 33.

The cover 2 is seated about the extension 10 below the knob and the washer 34 and likewise may be integrally removed with the cover 23. A gasket 35 is provided between the cover 2 and the shoulder 36 of the housing. A chamber 37 is formed between the cover 23 of the cartridge 15 and the cover 2 of the housing and from this the outlet 38 is connected in any suitable manner to the crankcase. The opening 38 is large enough to remove all oil filtered through or passed through the valve 25 without building any substantial pressure in the chamber 37. Normally, a 21/64" opening is sufficient.

A drain 39, fitted with a plug 40, is provided at the base of the sump.

The formation of the cartridge is of great importance in the production of a successful filter.

The material of the cartridge should be such that strong acid such as sulfuric, which may be formed in an internal combustion engine, will be chemically removed by the filtering material. Cellulosic fibers, such as cotton, paper and the like, will remove such acids, when formed, by reacting therewith. The material and its method of agglomeration must likewise be such as to prevent any substantial channeling of oil through the filter upon use. Channeling is extremely difficult to prevent, and any loose heterogeneous mass of material will channel badly unless special precautions are taken to prevent it. The cartridge should also be of such a density that it will permit oil to flow through it freely and yet remove from it the impurities, and likewise must have sufficient elasticity or rigidity that it will not compress markedly under the permitted stresses to which it is subjected. In the present filter, this requires a correlation between the pressure at which the valve 25 will open and the compression point of the cartridge. For example, a cartridge is hereinafter produced to withstand a pressure of the order of 40 pounds per square inch without noticeable compression, and accordingly the valve 25 is set so that the cartridge will not be subjected to any greater pressure drop across the cartridge. At the same time, in the present structure it is considered that the back pressure from the chamber 37 will be zero under the conditions where the operating pressure on the valve 25 exceeds 40 pounds and therefore the maximum pressure to which the cartridge is subjected, as well as the pressure drop across it, is limited to the compression point thereof.

In Fig. 5 is illustrated the preferred manner of producing the cartridge. The string material is pure cotton thread, free from lint and short ends and is what in the trade is known as thread stock 65 in knotted form, which consists of broken bobbins of various size threads. This material is known as No. 659 white yarn waste and preferably has a minimum thread size of 70, and a maximum not over 40. These threads form loose yarns containing about 10 to 200 threads in each strand. The strands having much more thread than this are discarded (generally those which have a diameter of more than 1 1/4" when loose). These strands are passed through rollers to crush the 70 knots, and then are ginned upon a large rotating

wheel having rows of teeth 4 to 5 inches apart and about an inch apart in the rows. The wheel has a diameter of about 40" and a width of about 12". It rotates at about 40 R. P. M. and the thread winds up upon it. The mass is then removed in the form of a band of loose yarn material, the broken groups or masses of threads being stretched out but not losing their identity. The loose or short ends are discarded, and the material is then weighed out in the desired amounts. A seven-foot section of this material contains about enough material for one cartridge. The requisite amount of material for a cartridge is measured, the rope of material is then divided about in half to form a fourteen-foot rope of 15 half the size, and is fed into the winding device shown in Fig. 5.

This device comprises a spindle 41 carrying a chuck 42, provided with two pins 43 which engage corresponding perforations 44 in the base of the cone 41, which has been fitted over the spindle from the other end. A cylinder 47 encloses the spindle. The spring 45, which is a lefthand wound helical, has previously been attached to the base of the cone, and its last convolution forms a triangular slot adjacent the base. A cover plate 46 is supplied at the opposite end of the spindle and is held in place by the block 48. In many instances, a small amount of the thread material is wrapped about the base of the cone 40 and under the spring, there sometimes being difficulty in securing complete and uniform stuffing at this point. The spindle is then rotated at about 60 R. P. M. in the direction such that the end of the cotton will be caught under the spring 35 and held there. The cotton is spread in a ribbon approximately the length of the cartridge and is fed through a slot 48 of about 3/8" diameter while held by the workman under considerable tension. The material is fed to produce a uniform cartridge, the strands being moved forward, if necessary, as one portion of the cartridge becomes filled. The tension provided is sufficient that 7 1/2 ounces of the cotton fibers will occupy 62 cubic inches of cartridge space. However, this may be varied, providing the cartridge is so supported as not to be compressible under operative conditions, from 6 to 9 ounces, and with certain types of packing, to as high as 10 1/2 to 11 ounces. If the material is wound too hard, it will expand 50 after removal from the cylinder. The cartridge preferably should be able to stand, with the spring, a compression limit of 40 pounds, plus or minus 5 pounds.

When the material has been filled in, it will 55 be in the form of circumferentially parallel or spirally wound fibers, tightly wound in and about the helical in such manner that channeling does not occur on use of the cartridge.

The bag 48 before the winding operation is attached to the top of the cone and lies flat along the spindle, a rubber band (not shown) holding it on the cone. At the close of the operation, the block 46 and plate 45 are removed and the stocking pulled over the outside of the cylinder 47. The cartridge is then pushed out of the cylinder by the chuck 42 into another friction member 50, which pulls the stocking 48 back and holds the cotton in, the stocking being stretched considerably and pulled down over the outside and fastened by a shirr string over the same of the cone.

A machine for carrying out the winding operation is described in greater detail in the patent of George C. Warner, No. 2,141,144, issued December 20, 1938.

The wire handle 49, shown in Fig. 7, is then inserted and passed underneath the upper loop of the helical, the open ends being spot-welded and drawn into the cartridge. Such a handle provides a positive non-corroding means of withdrawing the cartridge from the filter and eliminates the use of tools for this purpose.

A cartridge satisfactory for use in ordinary passenger car engines is $5\frac{1}{2}$ " long by 4" in diameter, and contains 69.2 cubic inches, of which 7.2 cubic inches is occupied by the hollow cone. This type of cartridge contains $7\frac{1}{2}$ ounces of cotton material. For other larger motors the larger cartridge is used, for example, with a truck motor, a 6" high cartridge of the same diameter and containing 9 ounces of cotton, may be employed.

A preferred size of cone has a base of $3\frac{3}{4}$ ", an internal diameter of 2 inches at the bottom, and a height of 3.75". With such a cone, a large number of small holes is preferred. For example, it has been found that holes of $\frac{1}{8}$ " in diameter, separated approximately $\frac{3}{16}$ ", beginning about an eighth of an inch above the base of the cone, and arranged in circumferential rows of holes about 10 deep, are preferred. This will provide approximately 250 holes extending approximately two inches into the cone.

The orifices 9 preferably discharge oil into the cone at a point about halfway between the top holes and the top of the cone.

The angle of the cone is so correlated to the flow of oil and the size of the sump that a quiescent body is provided within which impurities 35 may settle out of the oil. With the system shown, the oil moving from the orifices 9 impinges in a narrow moving stream upon the upper rigid walls of the cone in a manner to precipitate large impurities, but at the same time keep the walls of the cone clean. The oil then moves downwardly, 40 its area of flow increasing, and its velocity therefore decreasing, but sufficient velocity being maintained along the edges of the cone so that the wash of oil across the openings 12 is sufficient to keep them from clogging with impurities, 45 as is frequently the case where oil is discharged directly into a filtering medium. At the same time, at the lower portion of the cone and in the sump, a zone of quiescence is provided within 50 which heavy impurities may settle out.

The helical 15, which is anchored, as described, on the base of the cone, is formed of heavy steel material $\frac{1}{8}$ " in diameter and of sufficient strength to withstand 40 pounds compression 55 when combined with a mass of cotton material. This means generally that the spring will stand 10 pounds pressure at $3\frac{1}{8}$ " length without the cotton material.

The spring is $4\frac{1}{4}$ " high, has an external diameter at the bottom of $3\frac{3}{8}$ ", $2\frac{5}{8}$ " in the middle, and $5\frac{1}{8}$ " at the top. It is preferably shaped to follow the inclination of the cone, up to and including the first turn above the highest opening in the cone, and from that point on, the slope 65 of the helical is reversed to provide maximum support to the upper mass of filtering medium.

It is important in preparing the filter to correlate the mass of filtering medium to the amount of oil passing therethrough; to correlate the viscosity of the oil to the depth of the mass, and 70 also the depth of the mass to the area of it through which oil may enter. This means in many instances that doubling the inlet area for the oil means more than doubling the mass of filtering medium above it. For this reason, it

has been found advisable in many instances to use a dual installation in which a pair of cartridges are fed in a single system rather than to attempt to build a larger unit, inasmuch as there may be a considerable saving in the amount of material required.

It will be noted in the construction of filters shown that from the time the oil passes through the orifices 9 until it has completed its passage through the filter, its available area of flow is being constantly widened. Thus, after leaving the orifices the oil passes down the cone, the cross-sectional area of which is constantly increasing, and thereafter enters the cartridge at its narrowest point and flows upwardly therethrough, likewise with increasing cross-section. This permits better distribution of impurities throughout the cartridge, there being less of a tendency for all of them to be deposited at the beginning.

The shape of the cartridge also is such that impurities tending to settle out after long use do not clog the oil entrances, but in the event of such settling will be caught in the lower legs of the cartridge.

The construction of the filter is such that oil passing through it may be considered as being in several well defined pressure zones, which are induced by the various valve-like passages through which the oil is forced to proceed. For example, with a line pressure of 40 pounds, the pressure upon the valve 25 has been found to be 20 pounds (this test being with an S. A. E. 40 oil), the pressure in the sump 15 pounds, the pressure in the middle of the cartridge 13 pounds, and the pressure in the top of the filter housing 8 pounds. The pressure in the top is larger, due to the high viscosity of the oil, there being no substantial pressure in the top with a lighter or hotter oil. When the line pressure was reduced to 30 pounds with the same oil, the valve pressure became 15, the sump pressure 12, the cartridge pressure 10, and the return pressure $6\frac{1}{2}$.

The term "base" as applied to the filter cartridge herein is used to denote the side thereof from which the oil enters, regardless of the position thereof with respect to the vertical.

The following table shows typical satisfactory filter dimensions for ordinary truck and passenger car use. All dimensions are in inches.

	Truck	Passenger car	
Oil feed line 6.....	$3\frac{1}{8}$	$3\frac{1}{8}$	55
Orifice to tube.....	$3\frac{1}{8}$	$3\frac{1}{8}$	
Tube internal diameter.....	$3\frac{1}{8}$	$3\frac{1}{8}$	
Tube length.....	$8\frac{3}{4}$	$6\frac{3}{4}$	
Orifices 9 diameter.....	$3\frac{1}{8}$	$3\frac{1}{8}$	
Distance—orifice to cone.....	6	$5\frac{1}{2}$	
Cartridge height.....	(77.8)	62	
Cartridge volume.....	$4\frac{1}{4}$	4	60
Cartridge diameter.....	$4\frac{1}{4}$	4	
Cone diameter base.....	2	2	
Cone internal diameter at base.....	$3\frac{3}{4}$	$3\frac{3}{4}$	
Cone height.....	$3\frac{1}{8}$	$3\frac{1}{8}$	
Cone holes diameter.....	250	250	
Cone holes number.....	7.2	7.2	
Cone volume.....	$4\frac{1}{4}-5\frac{1}{4}$	$4\frac{1}{4}$

Sump depth.....	$2\frac{1}{4}$	$2\frac{1}{4}$	
Oil outlet diameter.....	$3\frac{1}{8}-3\frac{1}{16}$	$3\frac{1}{8}-3\frac{1}{16}$	
Outlet 24 diameter.....	9	$7\frac{1}{2}$	
Cartridge material weight, ounces.....			

This application is in part a division and in 70 part a continuation of my co-pending application, Serial No. 69,217, filed March 16, 1936, which was a continuation-in-part of my co-pending application, Serial No. 702,529, filed December 15, 1933.

The foregoing detailed description has been given for clearness of understanding only, and no unnecessary limitations should be understood therefrom, but the appended claims should be construed as broadly as permissible in view of the prior art.

I claim:

5. The method of winding a cartridge comprising a metallic base to which a metallic helix is axially affixed, which comprises winding by hand long cotton fibres about that portion of the helix immediately adjacent to the metallic base, and then winding the remainder of the cartridge by rotating the base and helix while feeding thereto a ribbon of long fibres longitudinally extending and predominantly unwoven, said ribbon containing substantially all of the material necessary to complete the cartridge, the ribbon being maintained under such tension that the fibers of the ribbon interlock to produce a cartridge substantially free from division lines, continuing the winding until the helix is embedded within the body of the fibres.
10. 2. A cartridge comprising a base, a helix centrally fastened to the base, and a mass of long cellulosic fibres spirally wound around and among the convolutions of the helix.
15. 3. The method of winding a cartridge which comprises securing a base member having attached thereto a flexible container upon a rotatable support within a cylinder, winding fibrous material upon the base within said cylinder, reversing said flexible container about the outside of the cylinder, pressing the wound cartridge out of the cylinder into the container, and fastening the container about the cartridge.

4. A filter cartridge comprising a mass of long cellulosic unwoven threads spirally wound about a central axis, said mass of threads having the structure resulting from winding under tension sufficient to cause interlock without division lines, of a wide irregular ribbon of long cellulosic individual loosely and irregularly associated threads predominantly unwoven, said threads extending longitudinally in the ribbon before winding and circumferentially of the cartridge after winding.

5. A filter cartridge comprising a base and a mass of long, predominantly unwoven, longitudinally extending threads, wound about the base and its circumferential axis, said mass of threads having the structure resulting from winding under tension sufficient to cause interlock without division lines, of a wide irregular ribbon of long cellulosic extending individual loosely and irregularly associated threads predominantly unwoven, said threads extending longitudinally in the ribbon before winding and circumferentially of the cartridge after winding.

6. The method of forming a cartridge which comprises forming an extended wide irregular ribbon of a multitude of longitudinally extending long cellulosic threads loosely and irregularly associated and predominantly unwoven in the ribbon, and winding the ribbon to form a cartridge under such tension that the fibers thereof interlock to form a cartridge free from division lines.

7. The method as set forth in claim 6 in which substantially the entire cartridge is formed from a single ribbon.
